US0D1024310S

(12) **United States Design Patent** (10) **Patent No.:** **US D1,024,310 S**
(45) **Date of Patent:** **** Apr. 23, 2024**

(54) **IMPLANT REMOVAL DEVICE**

(71) Applicant: **BATEMAN BOTTLE, LLC**,
Wilmington, DE (US)

(72) Inventors: **Michael Bateman**, Highland Ranch,
CO (US); **Andy E. Denison**, Temecula,
CA (US); **Peter J. D'Aquanni**,
Murrieta, CA (US)

(73) Assignee: **Bateman Bottle, LLC**, Wilmington, DE
(US)

(**) Term: **15 Years**

(21) Appl. No.: **29/685,427**

(22) Filed: **Mar. 28, 2019**

(51) LOC (14) Cl. **24-01**

(52) U.S. Cl.

USPC **D24/108**

(57) **CLAIM**

An ornamental design for an implant removal device, as shown and described.

DESCRIPTION

FIG. 1 is a front perspective view of implant removal device; FIG. 2 is a right side view of the implant removal device of FIG. 1;

FIG. 3 is a left side view of the implant removal device of FIG. 1;

FIG. 4 is a top view of the implant removal device of FIG. 1;

FIG. 5 is a bottom view of the implant removal device of FIG. 1;

FIG. 6 is a front view of the implant removal device of FIG. 1; and,

FIG. 7 is a rear view of the implant removal device of FIG. 1.

The broken lines depict portions of the implant removal device that form no part of the claimed design.

1 Claim, 6 Drawing Sheets
